UNITED STATES PATENT OFFICE.

ERNEST WALBRECKER, OF WYOMISSING, PENNSYLVANIA, ASSIGNOR TO THE NARROW FABRIC CO., OF WEST READING, PENNSYLVANIA, A CORPORATION OF PENNSYLVANIA.

DESIGN FOR A TRIMMING BRAID FOR GARMENTS.

Application filed February 6, 1923. Serial No. 5,094. Term of patent 7 years.

To all whom it may concern:

Be it known that I, ERNEST WALBRECKER, a citizen of the United States, residing at Wyomissing, in the county of Berks and State of Pennsylvania, have invented a certain new, original, and ornamental Design for Trimming Braids for Garments, of which the following is a specification, reference being had to the accompanying drawing, forming part thereof.

The figure is a plan view of a trimming braid for garments showing my new design.

I claim:

The ornamental design for a trimming braid for garments, as shown.

In testimony whereof I affix my signature.

ERNEST WALBRECKER.
